CASING HOOK

**George F. Fermier and John C. Stokes, Houston,
Tex., assignors to Reed Roller Bit Company,
Houston, Tex., a corporation of Texas**

Application June 20, 1936, Serial No. 86,255

18 Claims. (Cl. 294—82)

This invention relates to that type of hooks customarily employed in the construction and operation of oil and gas wells for supporting the casing or drill pipe employed during the drilling operation.

This invention has to do particularly with a resilient hook which will effectively support the weight of a portion of a drill pipe being unscrewed and which will lift such portion away from the part from which it is disconnected as soon as the threads are disengaged.

Hooks of this type are commonly used in putting in or pulling well casings or drill stems, to support a section of the casing while it is being unscrewed from the other sections. The separation of the sections is effected by rotating the casing or drill stem at a point below the joint to be broken by means of a rotary table while the section above the joint is held stationary by suitable tongs, or by holding stationary the casing or drill stem at a point below the joint to be broken while the section above the joint is rotated by means of tongs.

In either procedure some means is provided to take up the weight of the upper section during the breaking of the joint, because unless this is done, the weight of the section rests on the screw threads of the joint and tends to grind off and damage the threads. To obviate this damage to the screw threads, and for the purpose of saving time, it is common to support the section being removed by a casing hook provided with a compression spring of such strength as to support the section during the breaking out of the tapered-threaded joint, and later after disengagement of the threads to automatically lift said section high enough to free it from all interference with its former mating member.

Where such hooks are provided with merely a spring for lifting the pipe section once it has been disconnected, it has frequently been experienced that an operator is unable to push the section removed aside exactly the moment it is pulled upwardly by the spring, and that on the recoil the section removed will come back down and frequently hit against the joint from which it has just been disconnected. This is obviously detrimental to the threads of the joint and causes considerable damage and delay when it occurs. Furthermore, it is not an unknown occurrence for a workman's hand to slip between the sections when the section is first lifted, and to be greatly injured when the sections come together again on the recoil.

It is the purpose of this invention to provide a

casing hook in which the recoil referred to will be eliminated.

It is a further object of this invention to provide a casing hook which will serve to quickly remove the section from the joint from which it is disconnected, but which will retard any tendency toward recoil and prevent the two parts of the joint from being hammered together once they have been separated by the spring of the casing hook.

With the foregoing and other objects in view, this invention contemplates the various parts and combinations, and the various modifications thereof illustrated in the accompanying drawings.

It is to be understood, however, that while several modifications have been illustrated, the same are by way of example only, and it is not to be implied that all possible forms have been shown. It is apparent that various other modifications may be made within the spirit and scope of this invention, such spirit and scope being limited only by the prior art and by the terms of the appended claims.

Referring now more particularly to the drawings in which like numerals indicate corresponding parts throughout;

Fig. 1 is a view partly in vertical cross section illustrating one embodiment of this invention.

Fig. 2 is a horizontal section taken along the line 2—2 of Fig. 1, and illustrating the adjusting means employed in connection with the form shown in Fig. 1.

Figs. 3 to 8, inclusive, are views similar to Fig. 1, but illustrating various modified arrangements of the respective parts.

Figs. 1a, 4a and 8a are enlarged fractional portions of Figs. 1, 4 and 8, respectively.

Fig. 9 is a view illustrating the application of a casing hook constructed in accordance with this invention.

Referring first to the form shown in Fig. 1, the hook 1 is supported by means of a yoke 2 or the like, such yoke having eyelets 3 at its lower ends adapted to be received on the pintles 4 of the block 5. The eyelets 3 are held on the pintles 4 by means of cap screws 6 or the like which secure the washers 7 in place.

The block 5 is provided with a central bore having a reduced portion at its upper end within the externally threaded extension 8 of the block 5. Threaded onto this extension 8 is a tubular member or cylinder 9 which extends upwardly from the block. A passageway 10 constituting a bypass is formed through the extension 8 in a longitudinal direction and communicates with the inte-

rior of the tubing 9 and with the interior of the lower portion of the bore through the block 5. The size of this passageway 10 may be regulated by suitable means such as a screw valve 11. A second passageway 10', spaced from the passageway 10, also extends between the interior of the tubing 9 and with the interior of the lower portion of the bore through the block 5. This passageway 10' is controlled by a ball valve 11' which permits free movement therethrough in an upward direction but prevents movement therethrough in a downward direction.

The hook has a portion fitting within the lower part of the bore in the block 5 and provided with a cup-shaped washer 12 so as to form a fluid seal between this portion of the hook and the walls of the bore in the block. The walls 13 of this bore are machined smooth so that the packing or washer 12 may slide therein with the least possible friction and form a good seal. Above the washer 12 the hook 1 carries a stem 14 of reduced size, and the upper end of this stem is threaded at 15 to receive a nut 16 forming a plunger which rides up and down within the cylinder 9. At a point adjacent its lower end this plunger is provided with a cup-shaped washer 17 similar to the washer 12 on the lower portion of the hook with the exception that the washer 17 is inverted. The upper end of the nut 16 is provided with a head which extends laterally and limits the downward movement not only of the nut 16, but of the hook 1 as well. This nut 16 is locked in place by means of a lock nut 19.

Positioned below the lower end of the nut 16 and seated on the upper end of the extension 8 of the block 5 is a compression spring 20 which is adapted to support the weight as hereinbefore referred to. A plug or other means may be provided adjacent the upper end of the cylinder 9 for the purpose of at least partially filling this cylinder and the lower portion of the bore through the block 5 with a suitable liquid, which liquid will act with a dashpot effect when the hook is operated as will now be described.

The hook 1 is connected to a section of pipe and an upward pull exerted until the spring 20 is compressed to the extent that the force exerted by the spring will be sufficient to raise the section of pipe as soon as it is disconnected. When the section is disconnected, the force of the spring will cause the pipe to be raised quickly, the fluid passing freely upwardly through passageway 10', until the joint at the lower end of the pipe is free from the joint to which it has just been disconnected. The dashpot effect of the fluid now comes into play, the valve 11' closing and the fluid on its downward movement being forced past the metering screw 11. This prevents any rapid downward movement of the hook, and consequently of the pipe section which has just been removed. This dashpot arrangement thereby takes up the recoil which would ordinarily be taken up by the spring itself, and prevents the downward recoil movement which has been referred to above.

In the form illustrated in Fig. 3, the hook 21 is supported by the yoke 22, the lower ends of which are formed with eyelets 23 engaging the lugs 24 in a manner very similar to that illustrated in Fig. 1. The lugs 24 are carried on a block 25 which is for the most part hollow and open at its upper end, but which is provided with an upstanding cylindrical portion 26 centrally thereof. The cylindrical portion 26 when taken with

the outer walls of the block 25 provide an inner cylindrical chamber 27 and an outer annular chamber 28. Passing through the inner chamber is the stem 29 which is integral with the upper end of the hook 21, and surrounding this stem 29 is the compression spring 30 corresponding to the spring 20 of Fig. 1. The stem 29 is threaded at its upper end as at 31 to receive an inverted cup-shaped plunger member 32. This member 32 has downwardly extending walls 33 carrying at their lower ends an annular plunger 34 which is of such a size as to fit fairly snugly within the annular chamber 28. This plunger 34 is provided with a by-pass 35 extending from its upper to its lower surface. In addition to the by-pass 35 through the plunger 34, the block 25 is also provided with two or more by-passes. One of these by-passes 36 is normally closed to prevent movement of the fluid therethrough from the space below the plunger to the space above the same by means of a check valve 37. The check valve 37, however, is arranged to permit free movement of the fluid from the space above the plunger to the space below the same. The other by-pass 38 is likewise provided with a check valve 39, this check valve being spring pressed by a spring 40 to retard movement of fluid from below the plunger to the space above the same, and to positively prevent movement of fluid from the space above the plunger to the space below the same.

The upper end of the block 25 is preferably closed by a plate or dome 41 secured in place by means of cap screws or the like 42.

In this form, the operation is similar to that illustrated in Fig. 1 with the exception that upon upward movement of the hook 21 the fluid is permitted to pass freely through the by-pass 36 in the block 25 and thus permit the upward movement of the hook to be swift and sudden. On the other hand, the downward movement is limited both by the size of the opening 35 and by the strength of the spring 40 so that the recoil which it is desired to eliminate will be effectively damped.

With reference to the form illustrated in Fig. 4, this is very similar to that shown in Fig. 3. In this form the hook 43 is supported by the yoke 44 having the eyelets 45 in engagement with the lugs 46 on the block 47. An upstanding cylindrical wall 48 is provided within this block 47, the same being very similar to the wall 26 in Fig. 3. Passing through the chamber 49 within this cylindrical wall 48 is the stem 51 on the hook 43 and the spring 52 surrounds this stem in precisely the same manner as shown in Fig. 3. Secured to the threaded upper end 53 of the stem 51 is the plunger member 54 which has downwardly extending walls 55 carrying the annular plunger 56. In this instance, the annular plunger is so formed as to fit the annular chamber 50 loosely. The plunger is provided with a by-pass opening 57 therethrough similar to the opening 35 of Fig. 3. On the lower surface of this annular plunger there is mounted a U-shaped packing washer 58 secured in place by means of a ring 59 held to the plunger by cap screws 60 or the like. The upper end of the block 47 is closed by a plate or dome 61 held to the block by screws 62 in the manner readily apparent.

The operation of this hook is likewise similar to that shown in Fig. 3, the exception being that upon upward movement of the hook the fluid is allowed to pass from above the piston to the space below the piston by virtue of the shape of

the cup-shaped packing 58, the by-passes 36 and 38 in the block being omitted.

In the form shown in Fig. 5 a somewhat different arrangement is provided. The hook 63 in this instance is supported by a yoke 64 having eyelets 65 mounted on the lugs 66 of the block 67. The block 67, however, is provided with two cylindrical chambers therein 68 and 69, these chambers being connected at their lower ends by a passageway 70. There is also a passageway 71 which connects the upper ends of these cylindrical chambers, and which passes adjacent the lower end of the cylindrical chambers and adjacent the passageway 70. The passageways 70 and 71 are interconnected by means of a restricted opening 72, and also by means of an opening 73 controlled by a ball valve 74 normally urged into seated position by a spring 75. The lower ends of the chambers 68 and 69 are also connected to the passageway 71, these connections being controlled by the ball valves 76 and 77, respectively, so positioned as to permit passage of fluid from the passageway 71 into the respective chambers, but to prevent such passage in the opposite direction. The balls 76 and 77 are retained adjacent the openings they control by means of guards 78 and 79.

The upper ends of the chambers 68 and 69 are closed by means of plugs 80 and 81, respectively, threaded into the upper ends of the chambers. Each of these plugs is provided with an opening through which the piston rods 82 and 83 are adapted to move. These piston rods carry the pistons 84 and 85, respectively, and are connected at their upper ends by means of a cross head 86. The cross head 86 is secured to the upper end of the stem of the hook by means of a nut 87 or the like, the connection being loose so that the hook may swivel with respect to the plungers. The hook in this instance extends upwardly through the block, and is provided with a compression spring surrounding its stem in substantially the same manner as illustrated in Fig. 7 of the drawings.

In operation, the device of Fig. 5 permits rapid movement of the hook upwardly, the fluid within the cylindrical chambers 68 and 69 passing in such instance from the space above the pistons through the passageway 71 and into the space below the pistons through the valves 76 and 77. On downward movement, however, the hook is forced to move slowly by the dashpot effect created by the necessity for the fluid in moving from below the pistons to above the same to pass through the restricted opening 72, and through the passageway 73 controlled by the spring pressed valve 74.

In Fig. 6, the hook 88 is supported by a yoke 89 having eyelets 90 engaging the plugs 91 on the block 92 in substantially the same manner as hereinbefore described. The block 92, however, is in this instance formed with a single cylindrical chamber 93 and with a passageway 94 connecting the upper end of this chamber with the lower end thereof. Adjacent the lower end of the chamber this passageway 94 communicates with the interior of the chamber through a restricted opening 95, and at its lower end this passageway is controlled by a valve 96 retained in place by a guard 97. As will be seen, this valve is such as to permit free passage of fluid into the lower end of the chamber, but to prevent passage from the lower end of the chamber except through the restricted opening 95.

The upper end of the cylindrical chamber 93

is closed by a threaded plug 98 having an opening therethrough receiving the slideable piston rod 99. On its lower end this piston rod carries the piston 100 which is reciprocable in the cylindrical chamber and secured at its upper end is the cross head 101. This cross head 101 is secured to the stem of the hook 88 by a nut 102 or the like, these connections and the spring which surrounds the stem of the hook within the block 92 being substantially the same as that illustrated in Fig. 7 now to be described.

It will be appreciated that in this form the hook 88 is permitted to move upwardly without restriction, the fluid which is employed within the cylinder 93 passing in such instance from the upper portion of the cylinder to the lower portion of the cylinder through the valve 96. On its downward movement, however, it is restricted to passage through the small opening 95 and the recoil is thus substantially eliminated.

In Fig. 7, the arrangement is substantially the same as in Fig. 6, the hook 103 being supported by a yoke 104 which is in turn secured to the block 105 in substantially the same manner. The block 105 is similar provided with a single cylindrical chamber 106 and with a passageway 107 connecting the upper portion thereof with the lower portion thereof. The lower end of this passageway communicates with the interior of the chamber 106 through two openings, one of which is controlled by a spring pressed valve 108 held in place by a spring 109, and the other of which is controlled by a ball valve 110 retained by a guard 111. The upper end of the chamber is closed by a plug 112 formed to accommodate the piston rod 113 carrying a piston 114 at its lower end. At its upper end a cross head 115 is provided. By means of a castle nut 116, the cross head 115 is secured to a fitting 118 in such a manner as to permit the fitting to swivel with respect to the cross head. This fitting is in turn threaded at 119 to the upper end of the stem 120 on the hook 103. Surrounding the stem 120 between the lower portion of the block 105 and the fitting 118 is a compression spring 121, this spring having the same function as the springs illustrated in Figs. 1, 3 and 4.

In this form of hook, upward movement of the hook is permitted freely by virtue of the fact that the fluid which is used within the cylindrical chamber 106 may pass from above the piston through the passageway 107 and upwardly into the space below the piston through the valve 110. On downward movement, however, the fluid must pass by the spring pressed valve 108, the strength of the spring 109 being such as to damp the movement of the piston by restricting the movement of the fluid from below the piston.

In the illustration of Fig. 8, the hook 122 is supported by the yoke 123 having eyelets 124 on its lower ends engaging the plugs 125 on the block 126. The block 126 has a cylindrical chamber therein at 127, but is not provided with any passageways corresponding to those described in the preceding paragraphs. The upper end of the chamber 127 is closed by a plug 128 which is formed to provide for the passage of the piston rod 129. The piston 130 is carried on the lower end of this rod and fits loosely within the chamber 127. A cup-shaped packing 131 is secured to the lower face of the piston 130 by means of a plate 132 and cap screws or the like 133. Extending through the piston 130, the packing 131, and the plate 132, is a passageway 134 of such

size as to restrict the passage of fluid therethrough.

The upper end of the piston rod 129 is secured to a cross head 135 which is in turn secured to the upper end of the stem or hook 122 by means of a nut 136 or the like. The connection between the hook 122 and the nut 136 is similar in all respects to the corresponding structure shown in Fig. 7.

10 In this form, the upward movement of the hook 122 is unrestricted because of the fact that the fluid which is used in the chamber 121 may pass unrestrictedly by the piston 130 and the cup-shaped packing 131. On downward movement, however, the fluid is held by the packing 131 and is compelled to pass through the restricted passageway 134 in moving from below the piston to the space above the same. Any recoil is thereby taken up.

20 The application of the various casing hooks above described is illustrated in Fig. 9, the hook of Fig. 3 being shown here for purposes of illustration. It will be seen that the hook 21 in this instance is engaged with a yoke 137 secured to a clamp 138 by which the section of tubing 139 is being held. On the lower end of this section of tubing is the pin portion of a tool joint 140, the box portion 141 being on the upper end of the string of pipe 142. This string is in this instance supported by means of slips 143 carried by a suitably supported block 144 in a manner which is well known to those skilled in the art. When it is desired to disconnect a section such as 139, the section is pulled to a point above the support 144 and the slips 143 are then engaged to support the lower portion of the string of pipe. A sufficient force is exerted on the hook 21 to compress the spring 30 included therein, and to move the annular piston 34 to its lowermost position. The tool joint sections 140 and 141 are thereupon unscrewed to disjoint the section 139. Immediately upon disengagement of the threads of the respective parts of the tool joint the spring 30 will expand and cause the 30 annular piston 34 to be raised to its uppermost position within the annular chamber 28. In such movement fluid is permitted to pass from above the piston through the passageway 36 and pass the valve 37, no restriction being imposed upon this passage of fluid. This leaves the section 139 in the position illustrated in Fig. 9. Naturally, there is a tendency for a recoil to take place, and for this section to again move downwardly tending to bring the threaded ends of the tool joint into engagement the second time. This is prevented, however, in this instance by virtue of the fact that the fluid is trapped in the annular space below the piston 34, and before this piston can move downwardly, and hence before the hook 21 and the section 139 can move downwardly, the fluid must either pass through the small opening 35 in the piston, or must be forced past the spring pressed valve 39, and through the passageway 38. Since it requires considerable time for the fluid to pass from one space to the other by either of these routes, the tendency to recoil is effectively overcome.

In the foregoing description and in the following claims this invention has been referred to as a casing hook. It will be understood, however, that this term is not intended as in any way a limitation, but that it is intended that this invention shall include all hooks of the nature claimed which are capable of being employed either during the removal of a casing from a

well, or during the removal of a drill stem, or during the removal of any other pipe or rod from a well or other opening.

It will also be understood that the term "hook" is to be taken as including elements not necessarily shaped as hooks but performing the function of hooks disclosed in this application and that the term "yoke" is likewise to be taken as including elements shaped differently from the yoke elements disclosed in the drawing of this application but performing substantially the same function, namely, the function of a pendant support.

In view of the foregoing, it will be seen that a means has been provided for carrying out all 15 the objects and advantages sought by this invention.

Having described our invention, we claim:

1. In a casing hook, in combination, a yoke member, a spring supported thereby, a hook member supported on said spring, a dashpot having relatively movable parts connected to said yoke and to said hook, respectively, said dashpot including means for retarding without substantially restricting downward movement of said hook while permitting substantially free upward movement thereof with respect to said yoke.

2. In a casing hook, a yoke, a member carried by said yoke and having a fluid chamber therein, a spring carried by said member, a hook supported on said spring, a piston in said chamber and connected with said hook for movement in said chamber on upward or downward movement of said hook, and means for retarding a flow of fluid past said piston on downward movement of said hook and for conducting such fluid freely past said piston on upward movement of said hook, whereby said hook will be retarded on downward movement, and free from retardation on upward movement.

3. In a casing hook, a yoke, a member carried by said yoke and having a liquid chamber therein, a spring carried by said member, a hook supported on said spring, a plunger movable in said chamber and connected with said hook for movement in said chamber on downward movement of said hook, a liquid in said chamber, and means retarding the escape of said liquid from its position in said chamber ahead of said plunger on downward movement of said hook.

4. In a casing hook, a yoke, a member carried by said yoke and having a fluid chamber and a spring chamber therein, a spring in said spring chamber, a hook supported on said spring, a plunger in said fluid chamber and connected with said hook for movement in said chamber on downward movement of said hook, a fluid in said chamber, and means retarding the escape of said fluid from its position in said chamber ahead of said plunger upon downward movement of said hook.

5. In a casing hook, a yoke, a member carried by said yoke and having a fluid chamber and a spring chamber therein, a spring in said spring chamber, a hook supported on said spring, a plunger in said fluid chamber and connected with said hook for movement in said chamber on downward movement of said hook, a swivel connection between said hook and said plunger, a fluid in said chamber, and means retarding the escape of said fluid from its position in said chamber ahead of said plunger upon downward movement of said hook.

6. In a casing hook, a yoke, a member carried by said yoke and having a fluid chamber and a

5 spring chamber therein, said fluid and spring chambers being spaced laterally from each other, a spring in said spring chamber, a hook supported on said spring, a plunger in said fluid chamber and connected with said hook for movement in said chamber on downward movement of said hook, a fluid in said chamber, and means retarding the escape of said fluid from its position in said chamber ahead of said plunger upon 10 downward motion of said hook.

10 7. In a casing hook, a yoke, a member carried by said yoke and having a fluid chamber and a spring chamber therein, said fluid and spring chambers being substantially concentric with respect to each other, a spring in said spring chamber, a hook supported on said spring, a plunger in said fluid chamber and connected with said hook for movement in said chamber on downward movement of said hook, a fluid in said 15 chamber, and means retarding the escape of said fluid from its position in said chamber ahead of said plunger upon downward motion of said hook.

20 8. In a casing hook, a yoke, a member carried by said yoke, and having a fluid chamber and a spring chamber therein, a spring in said spring chamber, a hook supported on said spring, a piston in said fluid chamber and connected with said hook for movement in said chamber on downward movement of said hook, a fluid in said 25 chamber, means retarding the escape of said fluid from its position in said chamber ahead of said plunger upon downward motion of said hook.

30 9. In a casing hook, a yoke, a member carried by said yoke and having a fluid chamber and a spring chamber therein, said fluid and spring chambers being substantially concentric and said fluid chamber being of annular form, a spring in said spring chamber, a hook supported on said spring, an annular plunger in said annular fluid chamber and connected with said hook for movement in said chamber on downward movement of said hook, a fluid in said chamber, and means 35 retarding the escape of said fluid from its position in said chamber ahead of said piston upon downward motion of said hook.

35 10. In a casing hook, a yoke, a member carried by said yoke and having a liquid chamber therein, a spring carried by said member, a hook supported on said spring, a plunger movable in said chamber and connected with said hook for movement in said chamber on downward movement of said hook, a liquid in said chamber, and means 40 retarding the escape of said liquid from its position in said chamber ahead of said plunger upon downward motion of said hook and for freely admitting fluid to said chamber upon upward motion of said hook.

45 11. In a casing hook, a yoke, a member carried by said yoke and having a liquid chamber therein, a spring within said liquid chamber, a hook supported on said spring, a plunger movable in said chamber and connected with said hook for movement in said chamber on downward movement of said hook, a liquid in said chamber, and means 50 retarding the escape of said liquid from its position in said chamber ahead of said plunger upon downward motion of said hook.

55 12. In a casing hook, a yoke, a member carried by said yoke and having a fluid chamber and a spring chamber therein, said fluid and spring chambers being spaced laterally from each other, a spring in said spring chamber, a hook supported on said spring, a plunger in said fluid 60

chamber and connected to said hook for movement in said chamber on downward movement of said hook, a fluid in said chamber, said chamber having a restricted opening therein for permitting retarded escape of said fluid from its position in said chamber ahead of said plunger upon downward movement of said hook, and a freely operating check valve for freely admitting fluid to said chamber upon upward movement of said hook. 10

15 13. In a casing hook, a yoke, a member carried by said yoke and having a fluid chamber and a spring chamber therein, said fluid and spring chambers being spaced laterally from each other, a spring in said spring chamber, a hook supported on said spring, a plunger in said fluid chamber and connected with said hook for movement in said chamber on downward movement of said hook, a fluid in said chamber, said chamber having a restricted opening therein for permitting unrestricted escape of said fluid from its position in said chamber ahead of said plunger upon downward movement of said hook, a spring-pressed check valve arranged to permit additional escape of said fluid upon placing of an 25 excessive load on said hook, and a freely operating check valve for freely admitting fluid into said chamber upon upward movement of said hook.

30 14. In a casing hook, a yoke, a member carried by said yoke and having a fluid chamber and a spring chamber therein, said fluid and spring chambers being spaced laterally from each other, a spring in said spring chamber, a hook supported on said spring, a plunger in said fluid chamber 35 and connected with said hook for movement in said chamber on downward movement of said hook, a fluid in said chamber, a flexible cup-shaped washer on said plunger for preventing movement of said fluid between the walls of said chamber and the sides of said plunger upon downward movement of said hook, but permitting relatively free movement of said fluid in the opposite direction upon upward movement of said hook, and said plunger having a restricted passageway 40 therethrough for permitting retarded escape of said fluid from its position in said chamber ahead of said plunger upon downward motion of said hook.

45 15. In a casing hook, a yoke, a member carried by said yoke and having a fluid chamber and a spring chamber therein, said fluid and spring chambers being substantially concentric with respect to each other, a spring in said spring chamber, a hook supported on said spring, a plunger in said fluid chamber and connected with said hook for movement in said chamber on downward movement of said hook, a fluid in said chamber, said chamber having a restricted opening therein for permitting retarded escape of said fluid from 50 its position in said chamber ahead of said plunger upon downward movement of said hook, a spring-pressed check valve arranged to permit additional retarded escape of said fluid upon the placing of an excessive load on said hook, and a freely movable check valve arranged to freely admit fluid to said chamber upon upward movement of said hook. 55

60 16. In a casing hook, a yoke, a member carried by said yoke and having a fluid chamber and a spring chamber therein, said fluid and spring chambers being substantially concentric with respect to each other, a spring in said spring chamber, a hook supported on said spring, a plunger in said fluid chamber and connected with said 65 hook. 70

hook for movement in said chamber on downward movement of said hook, said structure having a restricted opening therein for permitting retarded escape of said fluid from its position in 5 said chamber ahead of said plunger upon downward movement of said hook, and a U-shaped washer on said plunger adapted to slidingly contact the walls of said chamber and prevent movement of said fluid past said plunger upon downward movement of said hook while permitting substantially free movement of said fluid past 10 said plunger upon upward movement of said hook.

17. In a casing hook, a yoke, a member carried 15 by said yoke and having a spring chamber and a plurality of fluid chambers therein, said fluid chambers occupying balanced positions on opposite sides of said spring chamber, a spring in said spring chamber, a hook supported on said spring, 20 plungers in said fluid chambers respectively, and each connected with said hook for movement in said chambers on downward movement of said hook, a fluid in said chambers, and means retarding the escape of said fluid from its position in

said chambers ahead of said plungers upon downward movement of said hook.

18. In a casing hook, a yoke, a member carried by said yoke and having a spring chamber and a plurality of fluid chambers therein, said fluid 5 chambers occupying balanced positions on opposite sides of said spring chamber, a spring in said spring chamber, a hook supported on said spring, plungers in said fluid chambers, respectively, and each connected with said hook for movement in 10 said chambers on downward movement of said hook, a fluid in said chambers, a restricted opening in said chamber for permitting retarded escape of said fluid from its position in said chamber ahead of said plunger upon downward movement of said hook, a spring-pressed check valve arranged to permit additional retarded escape of 15 said fluid from said chamber upon the placing of an excessive load on said hook, and a freely movable check valve arranged to freely admit fluid 20 into said chamber upon upward movement of said hook.

GEORGE F. FERMIER.
